(57) **CLAIM**

The ornamental design for a hair styling device as shown and described.

DESCRIPTION

FIG. 1 is a front, left and top perspective view of a hair styling device, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is an enlarged top plan view of the hair styling device.

FIG. 8 is an enlarged bottom plan view of the hair styling device.

FIG. 9 is an enlarged view of a portion of the hair styling device shown within the area designated as 9 in FIG. 1.

FIG. 10 is an enlarged view of a portion of the hair styling device shown within the area designated as 10 in FIG. 1.

FIG. 11 is an enlarged view of a portion of the hair styling device shown within the area designated as 11 in FIG. 2.

FIG. 12 is another front, left and top perspective view of the hair styling device of FIG. 1 shown in an environment of use.

FIG. 13 is another front, left and top perspective view of the hair styling device of FIG. 1 shown in an environment of use; and,

FIG. 14 is another front, left and top perspective view of the hair styling device of FIG. 1 shown in an environment of use.

The dashed broken lines depict portions of the hair styling device that form no part of the claimed design. The dot-dash broken lines in FIGS. 1-2 and 9-11 depict the bounds of the enlargements and form no part of the claimed design.

The additional dashed broken lines in FIGS. 12-14 depict environmental structures and form no part of the claimed design.

1 Claim, 14 Drawing Sheets
